UNITED STATES PATENT OFFICE.

ALBIN DANIELSON, OF BROOKLYN, NEW YORK, ASSIGNOR OF ONE-HALF TO HILMER JOHNSON, OF BROOKLYN, NEW YORK.

PROPELLER.

1,425,179.

Specification of Letters Patent.

Patented Aug. 8, 1922.

Application filed June 1, 1921. Serial No. 474,137.

To all whom it may concern:

Be it known that I, ALBIN DANIELSON, a citizen of the United States of America, residing at Brooklyn, county of Kings, State 5 of New York, have invented certain new and useful Improvements in Propellers, of which the following is a specification.

This invention relates to propellers for aeroplanes and the like, and the principal 10 object is to provide a device of this nature wherein the angle of the blades may be changed at the will of the operator.

Another object is to provide means whereby the blades may be moved to and held in 15 a neutral position in which the blades will merely "feather" through the air in rotation, so that very little resistance is offered in starting whereby a light form of self-starter may be installed for the engine.

Another object is to provide means whereby the blades may be rotated about a common axis, substantially parallel with their respective longitudinal axes so as to bring the effective posterior surfaces of the blades 25 into more or less direct thrust with the air operated on so as to control the rate of flight.

Another object is to provide means for rotating the blades about said common axis in the reverse direction so as to render the 30 anterior surfaces of the blades effective, thus acting as a brake, and reversing the effect of the propeller without reversing the direction of drive.

Another object is to provide common controlling means for effecting all of these 35 movements of the blades.

With these and other objects in view, which will be more apparent as the specification proceeds, the invention resides in certain 40 novel construction and combination and relation of parts, the essential features of which are hereinafter fully described, are particularly pointed out in the appended claims, and are illustrated in the accompanying drawings, in which:

Figure 1 is a side elevation of my improved propeller and attached mechanism.

Figure 2 is a front view of the same.

Figure 3 is a transverse section taken substantially in line 3—3 of Figure 1.

Figure 4 is a sectional view taken substantially in line 4—4 of Figure 3.

Like characters of reference refer to like parts in all views.

55 Referring to the accompanying drawing

in detail, 10 represents the propeller shaft which is in the form of a hollow tube and which may be rotated by any suitable train of mechanism from the motor or engine. Fixedly secured to or formed integrally with 60 the propeller shaft 10 is a pair of diametrically arranged trunnions 11.

A rod 12 is mounted for sliding movement in shaft 10 and is provided with a pair of collars 13 and 14 fixedly secured 65 to rod 12 and between these collars is confined a sleeve 15. Suitable bearings are provided at 16 between members 13 and 14 and the member 15. The sleeve 15 is provided with diametrically oppositely disposed ears 17 which protrude through slots 18 in the propeller shaft 10. The slots 18 extend to the forward end of the shaft where a cap 19 threadedly engages the end of shaft 10, said cap being provided with a 75 wrench socket 20.

The propeller blades are shown at 21 and are formed at their inner ends with cylindrical portions 22 seated in hafts or tubes 23. The blades are properly stream lined as required, and near the hafts each has a strengthening conical protuberance 24 formed on it. The hafts 23 are disposed on opposite sides of the drive shafts 10 with their axes parallel with the axis of the trunnions 11 and at right angles to the axis of the drive shaft 10. Hafts 23 are pivotally mounted on trunnions 11 by means of ears 25 formed integrally with or secured rigidly to the hafts 23. Links 26 connect ears 27 90 of the hafts 23 with respective ones of the ears 17.

It will now be seen that by moving the rod 12 forwardly, sleeve 15 will be moved forwardly and will draw with it links 26 95 which will cause the blades to move forward about the trunnions 11, whereby the posterior portions of the blades will be moved to meet the air at a greater angle or pitch whereby effecting driving of the aeroplane.

The blades are shown in Figure 1 as in the neutral position in which condition they merely cut the air in revolving and do not effect any movement of the plane. This is the position of the blades in starting so that 105 they create the least possible drag on the engine and a starter of much less power is required.

It will also be seen that the slots 18 extend rearwardly a short distance from neu- 110

tral position, so that by moving rod 12 rearwardly links 26 will be moved rearwardly to carry the blades beyond the neutral position and to such position that the anterior surfaces become effective and will act as a brake in slowing down the speed of the plane, and without changing the direction of drive of the propeller shaft.

Rod 12 passes rearwardly through the drive shaft 10 and near its rear end is provided with a threaded portion 28 which engages in the interiorly threaded hub of a hand wheel 29. The hub of wheel 29 may be swiveled in any suitable stationary frame or bracket 30 through which the rear end of shaft 12 extends and by which it is prevented from turning by a key of said bracket extending into a keyway 31 in said rod. An index finger 32 from said bracket overlays the wheel 29 upon which are suitably inscribed indices indicating "Forward" "Neutral" and "Reverse."

By operation of the hand wheel 29 the rod 12 is moved back and forth as desired.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. A propeller mechanism comprising a driving shaft, trunnions on said shaft, and blades arranged on opposite sides of said shaft and pivotally mounted on said trunnions. 35

2. In a device of the class described, the combination of a rotatable shaft, propeller blades hingedly mounted on said shaft, and a rod slidably mounted in said shaft and operable to effect movement of said blades 40 on their hinges. 45

3. In a device of the class described, the combination of a rotatable drive shaft, propeller blades hingedly secured to said shaft, and means for moving said blades on their 50 hinges so as to render them selectively effective for driving and for braking, and to render them ineffective at the will of the operator.

4. In a device of the class described, the combination of a rotatable drive shaft, propeller blades hingedly secured to said shaft, a rod slidably mounted in said shaft, and links operable by said rod for effecting movement of said blades on their hinges. 55 60

In testimony whereof, I affix my signature to this specification in the presence of two subscribing witnesses this 17th day of March, 1921.

ALBIN DANIELSON.
